WINDOW STRUCTURE

Tito A. Ferri, Miami, Fla., assignor of one-half
to Charles I. Girschowitch, New York, N. Y.

Application June 5, 1946, Serial No. 674,506

1 Claim. (Cl. 189—69)

1

This invention relates to improvements in window structures and has particular reference to windows of the horizontally swinging type.

It is an object of the present invention to provide a preferably all metal window structure constructed in such manner that a plurality of glass supporting sashes are supported for swinging movement outwardly and upwardly for affording ventilation while at the same time preventing the entrance of rain or other similar foreign matter and at the same time so mount the sashes at the hinges so that the hinge pin of either hinge can be removed or inserted while the sash is open and held against falling by the operating mechanism.

A further object is the provision of operating brackets for the several panels constructed in such manner that they may be individually adjusted to the ends of the several sashes to compensate for the "play" that may exist in the couplings of the various operating elements and thus provide for the assurance of an even swinging and closing of the panels to a uniform closure fit.

Another and important object of the invention resides in the structural arrangement of the main supporting frame, with removable inner face plates to facilitate the mounting of the structure in the wall of a building and preformed grooves for the reception of interfitting portions of the sashes as a weather tight closure joint and hinge protection and also guide grooves for the sliding reception of the end pins of Venetian blinds.

A further object resides in the provision of locking means for positively retaining the panels in closed position against accidental displacement and rattling.

Other and important objects of the invention will present themselves during the course of the following description, reference being had to the accompanying drawings, where;

Figure 1 is an outer face view of a window constructed in accordance with the invention,

Figure 2 is a horizontal section taken on line 2—2 of Figure 1,

Figure 3 is an edge elevation of the completed window, looking from the left of Figure 1,

Figure 4 is a vertical section taken on line 4—4 of Figure 1,

Figure 5 is an enlarged outer face view of a portion of the window, with parts broken away for sake of clearness and with same broken away centrally to illustrate the hinge structure,

Figure 6 is a fragmentary end view of one of

2

the window panels illustrating an adjustable operating bracket,

Figure 7 is a section taken on line 7—7 of Figure 4,

Figure 8 is a section on line 8—8 of Figure 7,

Figure 9 is a fragmentary inner face view of a parting rail and its adjacent panels, illustrating a panel lock and,

Figure 10 is a top plan view of the structure of Figure 9.

Referring specifically to the drawings, wherein like numerals are employed to designate like parts throughout, 5 designates the main frame of the window, preferably formed of any light weight metal, such as aluminum, either square or rectangular in shape. The frame 5 is generally channel shaped in cross section and comprises jambs 6 and top member 7 and sill 8, all suitably joined together by welding or otherwise into a rigid frame. For facility in mounting the frame in the wall of a building, the inner face of the respective parts are formed as removable face plates 9, suitably and rigidly held to short flanges 10, by screws or like fastenings. The removable plates

25 9 further facilitate the various adjustments to the sashes, to be described. The parts 6, 7 and 8 pressed inwardly to provide an annular internal rib 11 and from this rib, the side runs are pressed outwardly to form a wall 12, parallel with the main, relatively wide inner wall of the channels

30 13. The metal of the jambs 6 from the walls 12 are then pressed at a right angle to form the outer face of the jambs 6 as at 14. Vertical grooves 15 are pressed into the faces 14 for the reception of flanges carried by the sashes and to be described.

The top member 7 and sill 8 are continued outwardly from the rib 11 and bent upwardly and downwardly to form the face plates 16 and 17, lying in the same plane as the face plates 14 and joined at the corners in a customary manner. The formation of the walls 12, offset from the rib 11 and extending throughout the vertical length of the channels 6, provide a recess or pocket for the reception of window sashes, to be described.

Positioned across the opening of the frame 5, parallel and equidistantly spaced and lying within the recess, are a pair of parting rails 18, riveted or otherwise rigidly secured, as at 19, to the inner walls of the recess. The rails 18 are spaced to provide a plurality of rectangular openings to be covered by the hereinafter described sashes. These rails are preferably formed of aluminum or other light weight non-corrosive metal. The rails 18 are T-shaped in cross section and the

heads of the T are toward the inner side of the frame, as clearly shown in Figure 4.

Mounted for swinging movement in a horizontal plane and adapted to cover and uncover the openings formed by the frame 5 and rails 18, are a plurality of sashes 20, three openings and three sashes being illustrated, although it being obvious that this number may be increased or decreased as desired. Each sash comprises a rectangular frame 21 of channel formation and adapted to lie within the pocket of the frame 5. Each channel frame 21 is provided upon its upper horizontal portion with two hinge sections 22, preferably adjacent the ends of the frames and spaced apart at their inner ends. These hinge sections interfit and co-act with hinge sections 23 fixed upon the under side of the rails 18. Hinge pins 24 normally retain the hinge sections in co-operative relation for supporting the panels 20 swingably. The pins 24 are removable endwise for dismounting the panels and sufficient space is provided between the inner ends of the hinges to permit sliding movement of the pins 24 for complete removal. The co-acting hinge section 23 for the uppermost panel is carried by the inner portion of the channel 7, as shown. Each frame 21 supports a sheet of glass or other transparent material 25, suitably supported therein by any suitable means, as clearly shown in Figure 4.

The several frames 21 are provided with overlapping flanges 26 along their lower horizontal portions and these flanges are continued along the vertical end portions, as shown in Figure 2. The flanges of the end portions are provided with inturned flanges 27, adapted to enter the grooves 15 when the panels are in the closed position. The horizontal flanges 26 are sufficiently wide to entirely cover the hinge connections of the panel below. Thus it will be seen that an adequate weather protection has been provided by the flanges 26 and the interfitting flanges 27. Any suitable permanent flange, not shown, may be employed to cover the uppermost hinge connections.

It will be seen from the description so far given that a very novel mounting for horizontally swung windows has been provided. The structure presented is such that a mechanic, with a minimum of effort may mount or dismount the panels without the necessity of climbing to the outside of the window for removal of screws or other like conventional mountings. He merely opens the sashes and reaches out to remove the hinge pins 24, the only external member that must be removed in order to remove the sash.

Means are provided to swing the several sashes in unison upon their hinges, comprising a plurality of operating brackets 28, secured to the ends of the panel frames adjacent their tops. The brackets 28 are arcuate shaped, one free end being provided with a swivel pin connection 29 and the opposite end being attached to the frame by a pivot rivet 30 and adjusting screw 31. The screw 31 passes through an arcuate slot 32 in the bracket and the arc of the slot 32 and the arc of the bracket are struck from the center of the hinges 22 and 23. For attaining a maximum swinging arc to the panels 20, these brackets are elongated and the pin connection 29 is arranged an appreciable distance above the hinge point. Thus, with the connection 29 so arranged, it will enable the operator to swing the sashes 20 in an arc of approximately 90 degrees, a greater movement than any other window now in use. The adjustable screw and slot 31 and 32 enables the

mechanic to adjust to a fine point the clearance of all the sashes, where certain irregularities may exist in the structure and in the connections between the various elements of the operating devices and this fine adjustment assures that all panels will function identically, both in open and closed positions. After the adjustment has been made, the screw 31 is firmly set.

The brackets 28 pass through clearance openings 33, formed in the jambs 6 and normally lie within the channel of the jambs 6. The several brackets 28 at each end of the window are connected by a common operating rod 34, see particularly Figure 3 and the connecting pins 35 for each bracket are easily and quickly removable by a mechanic when it is desired to dismount a sash. Links 36 have connection with the pins 35 of the lowermost brackets and these links in turn are connected with crank arms 37, as at 38. The crank arms 37 are fast upon a rock shaft 39, supported in bearings 40 mounted within the channel of the sill 8. The shaft passes at one end through an operating gear box 41, rigidly supported upon a bracket 42 carried by the sill 8 and has splined thereto within the gear box, a worm wheel 43, operated through the medium of a worm 44. The worm 44 is fixed upon an operating shaft 45, suitably supported in the box and passes outwardly of the removable face plate 9 to be engaged by a hand crank 46. The shaft 45 at its inner end preferably engages a thrust bearing 47, in the present instance being a ball bearing. A wear adjustment collar 48 may be employed to adjust the shaft 45. It will thus be seen, that rocking of the crank 46 results in the rocking of the shaft 39, moving the crank arms 37 downwardly and through the links 36 and operating rods 34 causes the brackets 28 to swing outwardly for in turn moving the sashes 20 outwardly in an arc upon their hinges. The worm and worm wheel 44 and 43 provide a positive lock for the panels in any position of adjustment. The various brackets, operating rods and links and the gear box are all accessible to the mechanic upon a removal of the plates 9.

It may be found desirable at times to provide an additional locking feature for the sashes, as in windy weather, when there is a tendency for the sashes to rattle and to provide for this emergency, pivoted latches 49 may be mounted upon the rails 18, intermediate their ends and these latches may engage in any suitable keeper 50 carried by the lower channel member of the sashes and projecting inwardly a sufficient distance to be engaged by the latch 49.

Each of the jambs 6 are provided with grooves 51 in their inner face for the sliding reception of the end pins of Venetian blinds, indicated in dotted lines at 52. An insect screen may be arranged in the frame end, as indicated in dotted lines at 53, is positioned in a manner to abut the rib 11. Suitable securing means for the screen 53 may be employed.

Due to the operating connections and the hinges that support the respective sashes, the sashes can be swung open when it is desired to repair broken glass or panes, and the respective pins 24 one at a time can be slid inwardly and removed to free the hinge elements of the frame 70 and sash. Due to the fact that the levers 31, links 36, rods 34 and the brackets 28, the sash will be supported, and particularly so as the brackets in conjunction with the slots 33, the latter acting then as fulcrums, acts to hold the 75 parts so that the released sash may be moved

outwardly and away from the frame to permit easy access to the desired sash. This is a very important feature of this structure, and particularly where the entire structure with the exception of the panes, is made of aluminum.

From the foregoing, it is believed that a window structure has been described that is most novel in the arrangement of parts, the method of operation and the accessibility of the various detail operating features. The main frame may be fabricated in any desired manner and the complete window assembled for installation. All adjustments are conveniently made after the window has been installed and when completed and the plates 9 replaced, presents a finished appearance from both the inside and outside. All parts are preferably light weight, non-corrosive metal, assuring a maximum life with ease of operation. A mechanic can easily and quickly remove a panel by first removing the hinge pins, then the plates 9 for a removal of the particular pins 35, after which the panel can be lifted from the frame for replacement of glass, painting or the like.

This application is a continuation-in-part of 25 my application Serial No. 508,294, filed October 29, 1943, entitled Window Operating Mechanism.

Having described my invention, what I claim is:

In a window structure, the combination of a frame having a head, two side jambs and a sill, a plurality of cross bars spanning the space and anchored in the jambs and providing hinge receiving portions open exteriorly of the frame, two relatively long hinges to each cross bar and the head of the frame, a plurality of sashes, one 35 to each space provided by the head and the cross

bars, companion hinge elements carried by each sash for connection with the respective hinges of the head and cross bars, a slideable pin to each hinge, the space between the hinges of each sash 5 being sufficiently long to permit the insertion and withdrawal of the pins one at a time in a straight line movement, a pair of operating brackets connected to each sash and having their free ends projecting into the respective jambs, a rock shaft journaled within the sill and having its respective ends thereof projecting below the lower ends of the jambs, a crank arm connected to each end of the rock shaft, a plurality of operating rods mounted in each jamb and connecting the aligned operating brackets and crank arm and a manually operated gearing carried by the rock shaft and the frame, whereby the sashes can be moved in unison.
